UNITED STATES PATENT OFFICE.

JOHN M. YOUNG, OF BURLINGTON, PENNSYLVANIA.

WAGON-JACK.

SPECIFICATION forming part of Letters Patent No. 363,038, dated May 17, 1887.

Application filed September 25, 1886. Serial No. 214,546. (No model.)

To all whom it may concern:

Be it known that I, JOHN M. YOUNG, a citizen of the United States, residing at Burlington, in the county of Bradford and State 5 of Pennsylvania, have invented certain new and useful Improvements in Wagon-Jacks; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 Similar letters of reference indicate corresponding parts in all the figures.

Figure 1 is a side elevation of my improved wagon-jack. Fig. 2 is a front elevation of the same. Fig. 3 is a plan view of the same.

20 The object of this invention is to provide wagon-jacks simple in construction and convenient for use, and which can be operated from a position out from under the wagon, thus avoiding the necessity of the operator 25 stooping or reaching under the wagon to place or operate the same. I attain these objects by certain constructions and combinations of the various parts of the wagon-jack, in which 30 consists my invention, as will hereinafter be fully described, and then claimed.

A represents the sill, which is provided with an upright frame, B, and standard C, each mortised into and securely bolted to its sides at 1, 2, 3, and 4, and also provided with 35 fulcrum-bearings G G, between which a lever, D, is pivoted at p. On the short arm of the lever a cam, D', is formed, of the shape shown in Fig. 1 by the partially-dotted line. The frame incloses a head-block, E, the lower end 40 of which rests on the cam-shaped head of the lever D, its upper end having one or more

shoulders, a, below its top b, so as to adapt it to wagons of different heights. It is also provided with a slot, S, by which its movement is limited by the fixed pin f, passing through 45 the frame B. The standard C is ratchet-faced to engage a plate attached to the side of the handle of the lever D and hold it in the desired position when the weight is on the head-block E.

50 By means of the peculiar shape of the cam-head of my lever D, and by placing the fulcrum of the lever out from under the head-block E in the bearings G G, the block can be sufficiently lowered by elevating the handle 55 of the cam-headed lever D comparatively a short distance from the sill A, thus making it practical to use a long lever and correspondingly-long sill, so that the handle of the lever can extend out from under the wagon and the 60 object desired by my invention be attained.

Having thus fully described my invention, I claim as new and desire to secure my Letters Patent—

65 In a wagon-jack, in combination with the frame, the head-block sliding within the frame and provided with a head and a shoulder, by which it is adapted to wagons of different heights, and having a slot by which its movement is limited, the lever having a cam-shaped 70 head, as shown, extending into the frame and supporting and bearing directly on the bottom of the head-block, but not connected thereto, and the lever fulcrumed in bearings outside of the head-block, substantially as 75 and for the purpose described.

In testimony whereof I affix my signature in presence of two witnesses.

JOHN M. YOUNG.

Witnesses:

W. L. CALKINS,
JOHN J. SPALDING.
